UNITED STATES PATENT OFFICE.

WILLIAM W. WILE, OF AUBURN, INDIANA.

GRATE-BAR.

SPECIFICATION forming part of Letters Patent No. 635,989, dated October 31, 1899.

Application filed February 16, 1899, Serial No. 705,614. (No model.)

To all whom it may concern:

Be it known that I, WILLIAM W. WILE, a citizen of the United States, residing at Auburn, in the county of De Kalb, in the State of Indiana, have invented certain new and useful Improvements in Grate-Bars; and I do hereby declare that the following is a full, clear, and exact description of the invention, which will enable others skilled in the art to 10 which it appertains to make and use the same, reference being had to the accompanying drawings, which form part of this specification.

My invention relates to improvements in 15 hollow grate-bars.

The object of my present invention is to provide a hollow grate-bar of simple and economical construction having a vertically-adjustable hollow blast-bar, so arranged as to 20 afford either a solid blast or the natural draft, at the pleasure of the operator.

My invention consists of a two-part hollow blast grate-bar formed of a shell-body whose upper face is provided with a series of blast- 25 openings and a hollow blast-bar section adjustably mounted adjacent to the lower face of said shell-body and having upon its upper face a series of twyer-openings or vertical longitudinally-apertured bosses in register with 30 the said blast openings of the shell-body, means for securing said blast-bar in position, and means for adjusting the said blast-bar into position for the solid blast or into position for the natural draft, as the operator may 35 desire.

The principal novel features of my invention are the vertically-adjustable hollow blast-bar section and the means for making such adjustment.

Similar reference-numerals in the accompanying drawings indicate like parts in the several views, in which—

Figure 1 is a longitudinal central vertical section of my invention, showing the hollow blast-bar in its uppermost limit of vertical adjustment and in position for the employment of the solid blast. Fig. 2 is also a longitudinal central vertical section of the same, showing the hollow blast-bar in its lower limit of vertical adjustment and in position for the use of the natural draft. Fig. 3 is a perspective view

of the shell-body, showing the blast-openings in its upper face. Fig. 4 is a transverse section of Fig. 1, showing the means for adjusting the blast-bar. Fig. 5 is a transverse section of Fig. 2.

All parts of my improved grate-bar are made of suitable metal and of any desired size or proportions.

The grate-bar body, shell, or casing 1 may 60 have its upper face either flat or laterally inclined from a longitudinal line midway its sides, if desired, though it is preferably flat, as shown, the said face being provided with a series of vertical blast-openings 2, resembling 65 in outline the frustum of a cone. The said shell-body 1 is provided with pendent vertical integral sides 3, whose arrangement serves to induce a proper draft about the sides and over the top of the hollow blast-bar when desired. These sides 3, in conjunction with the transverse pendent integral webs 4, serve to 70 securely brace the said shell-body against warping in a well-understood manner. The hollow blast-bar 5, of any desired form or contour, is adjustably mounted adjacent to the lower face of the said shell-body by means of the supporting-bolts 6, which are arranged in suitable perforations midway the sides and a proper distance from the ends thereof. The 80 blast-bar 5 is provided at each end thereof with a lug or horizontal extension 7, having suitable bolt-holes in register with the said bolt-openings in the shell-body. In these 85 openings the bolts 6 are loosely arranged, the heads of which are preferably countersunk, and the threaded ends are provided with proper nuts 8. The upper surface of the said blast-bar is provided with a series of conical upright bosses 9, preferably arranged in three 90 or more longitudinal rows, as shown, and adapted to register with and be received by the said blast-openings in the said shell-body 1 when the solid blast is employed. These 95 bosses have a longitudinal central opening 10, communicating with the interior of said blast-bar 5, as shown. It is found that by making the said openings 10 conical in form they tend to focus and perceptibly augment the force of the blast through the same. The 100 forward end of the said blast-bar 5 is provided upon its lower face, and preferably near

the forward end thereof, with a pendent boss 11, having a twyer-opening 12, connected in a well-understood or other proper manner with a suitable blast. As the blast-bar 5 is loosely 5 or slidably mounted upon the bolts 6 and adapted for a limited vertical adjustment thereon, it is entirely supported in its uppermost position by the cams 13, which are rigidly mounted on the transverse shafts 14, 10 which are loosely mounted in suitable bearings in the lower end of suitable hangers 15, fixed upon the side of said shell-body, and are arranged one near each end of said bar. One end of the said shaft 14 is provided with a 15 proper crank-handle 16 for operating the same. The blast-openings 2 of the said grate-bar body are of sufficient diameter to afford an annular space for more or less natural draft about the said conical bosses 9 when the 20 said blast-bar is in its uppermost limit of adjustment, as shown in Figs. 1 and 4. As shown in Figs. 1 and 2, a proper blank space is left in the upper face of the blast-bar, above the said twyer-openings, to afford a more even 25 distribution of the blast to the said registering openings.

The operation of my invention is, briefly stated, as follows: If the operator desires to employ the solid blast, he so rotates the said 30 transverse shafts 14 that the said cams 13 elevate the said blast-bar to its uppermost limit, as shown in Figs. 1 and 4, whereby the said apertured bosses thereof register with the said enlarged conical openings of the grate-body. 35 1. When the blast fills the hollow blast-bar 5, it will evenly distribute itself to the fuel through the openings in the bosses 9 and the coincident blast-openings 2. The natural draft at the same time has a free circulation 40 about the blast-bar and through the said enlarged openings 2, thereby preventing undue heating and warping of the same. When the operator desires to employ the natural or open draft only, he so rotates the said shafts 14 by 45 means of the crank-handle 16 as to lower the said hollow blast-bar to the lowest limit of its vertical adjustment, as shown in Figs. 2 and 5, thereby leaving the blast-openings 2 of the shell-body free and unobstructed and giving 50 the natural draft free access to the furnace-fuel. Such sediment as accumulates in the said blast-bar 5 can readily be removed through the furnace-opening 17, of any proper construction.

55 Obviously my improved blast-bar is conveniently adjustable for the employment of either the natural draft or the solid blast and

can readily be detached by removing the nut on the lower end of the bolts 6.

What I desire to secure by Letters Patent 60 is—

1. In a hollow grate-bar, the combination of a shell-body having pendent draft-inducing sides as shown, and provided with a series of blast-openings upon its fuel-surface; 65 a hollow blast-bar 5 provided upon its upper surface with a series of upright bosses apertured as shown, and adapted to register with the said openings in the shell-body; means for suspending said blast-bar from the extended ends of said shell-body in a position of vertical adjustment; and means for vertically adjusting the said blast-bar as and for the purpose described.

2. The combination of a shell-body having 75 a series of blast-openings upon its fuel-surface; a hollow blast-bar suspended from said shell-body, provided upon its upper surface with a series of upright apertured bosses in register with said blast-openings and adapted 80 to be received thereby, as described; and means for vertically adjusting said blast-bar for the purpose of employing either the solid blast or the natural draft, all substantially as described.

85 3. In a hollow grate-bar, a shell-body 1 having pendent sides and a series of blast-openings upon its fuel-surface; a hollow blast-bar 5 suspended as shown from the said shell-body by means of the bolts 6, whereby it is adapted 90 for a limited vertical adjustment on said bolts for the purpose specified, the said bar being provided upon its upper surface with a series of upright bosses having conical longitudinal openings therein, and adapted to register with 95 the coincident openings in the fuel-surface of said shell-body; and means for vertically adjusting the said blast-bar consisting of pendent hangers 15 fixed as shown on the shell-body; the transverse shafts 14 rotatably 100 mounted in said hangers as described, and provided upon their outer end with an operating-handle; and the cams 13 rigidly fixed 105 upon said shafts and arranged in coöperative relation with said blast-bar for the purpose specified.

Signed by me at Auburn, in the county of De Kalb and State of Indiana, this 11th day of February, A. D. 1899.

WILLIAM W. WILE.
